UNITED STATES PATENT OFFICE.

ADOLPH WEISMAN, OF BROOKLYN, NEW YORK.

METAL BED.

Application filed August 22, 1924. Serial No. 733,520.

To all whom it may concern:

Be it known that I, ADOLPH WEISMAN, a citizen of the United States, and resident of Brooklyn, in the county of Kings and State of New York, have invented certain new and useful Improvements in Metal Beds, of which the following is a specification.

It is among the objects of the present invention to provide a metal bed that will closely simulate the appearance of a wooden bedstead, which will be of light, strong, sanitary, and durable construction and which may be manufactured with comparative economy.

When a metal bedstead is provided with square or other tubing of substantial transverse dimensions extending about the periphery of the end panels to frame or bind the latter, it lacks the desired characteristic appearance of a wooden bed of modern design, the end panel of which is of substantial thickness and devoid of any thick bordering bead structure.

In accordance with my invention, I preferably employ hollow panels consisting of two spaced relatively thin sheets of bendable metal and finish the edges of the panels by turning over the upper edges of the sheets and welding them together thus eliminating the usual bead, and closely simulating a wooden bed end.

A feature of the invention is the novel method used in manufacturing the panels, particularly the method by which I form hollow wing panels to supplement the head and foot boards, such wing panels being of transverse curvature and having preferably a compoundly curved upper edge. The method preferably consists in bending the two panel sheets about a template turning the edges of the sheets over the edge of the template, hammering down the turned over edges to render the excess metal inconspicuous, welding the edges together and polishing off the weld to render the same practically un-noticeable.

With the above noted and other objects in view, the invention consists in certain novel features of construction, methods of manufacturing, and arrangements of parts as will be more fully hereinafter described and pointed out in the claims.

The method of making the bed and the elements thereof are not claimed herein, but constitutes the subject-matter of my

c pending application, Serial No. 15,608, filed March 14, 1925.

In the accompanying drawings, which are illustrative of one embodiment of the invention

Figure 1 is a fragmentary perspective view of the bed.

Figure 2 is a vertical sectional view on the line 2—2 of Figure 1:

Figure 3 is a transverse sectional view on the line 3—3 of Figure 1:

Figure 4 is a side view of one of the hollow posts:

Figure 5 is a perspective view showing a formed wing panel being removed from its template.

Wooden bedsteads of conventional and modern design are formed with end panels which usually consist in a single wooden slab relatively heavy and presenting an untrimmed, unbordered curving upper edge which heretofore have never been successfully simulated by metal bed manufacturers.

The present invention has to do primarily with the construction of the two end pieces, namely the head piece and the foot piece of a metal bed and for purposes of illustration, I have shown merely a single end piece which for convenience of description, may be considered as an upright foot piece. The construction of the head piece would be substantially the same except the head pieces are made higher.

The foot piece end of the bed includes a pair of hollow legs 10, 10 mounting between them a hollow metallic panel 11 which constitutes the foot board. The foot board may be supplemented by the use of a pair of rearwardly curving wing portions 12 and 13 in the event the latter are used, legs 13, 13 would be employed to assist the legs 10 in supporting them.

The present invention resides partially in the novel method of forming these three panels. In forming the foot board panel I take a pair of metallic sheets 11^a, 11^b, of approximately similar size and of the correct shape and interpose between them, a flat template having an upper edge of the general curvature indicated in the drawings. The side edges of the sheet 11^a are folded around the side edges of the template into abutting relationship with the flat face of the sheet 11^b thereby forming spacer flanges 14. The upper edges of both sheets are folded over the curved edge of the tem-

plate, hammered down and welded together at 15 along the median line of the template edge. This operation leaves the lateral edges of the sheet 11^b extending beyond the turned in edges of the other sheet as indicated at 16. The template may be removed through the open bottom of the panel and the panel joined to the legs 13 by forcing the edges of the former into the longitudinal slots 17 in the legs. Preferably the panels are also welded at 18 to the legs to strengthen this frictional union.

For closing the open lower end of the panel, I employ a closure strip 19 formed at opposite edges with turned over beads 21 which may embrace and be welded at 20 to the lower ends of the plates 11^a, 11^b. The beads of the closure strip enter notches 21^a in the posts and at the edges of the slot 17. If desired, a hollow transverse apron 26 fitting snugly against the under face of closure strip 19 may connect the legs immediately below the panel and serve as an additional strengthening brace. The turned over edges 27 of the plates forming the apron may be overlapped if desired, but need not be welded since their union is ordinarily concealed.

The method of forming the curved panels 30 for the end wings involves certain additional operations because of the longitudinal curvature of the template 22 on which they are formed and the compound curvature of the upper edges of such template. The two 35 plates or sheets of metal 13^a, 13^b, used in forming wing panels are cut to proper shape and then bent longitudinally by a hammering operation in order to properly conform them with the longitudinal curvature of 40 the template. The side edges of plate 13^a are bent around the edges of the template to define spacer flanges and the upper edges of both of the sheets folded over the curved upper edge of the template. This folding 45 operation is completed by a hammering operation using the template as an anvil and flattening out the turned over upper edges of the sheets in so far as possible, so that the excess metal at the upper edges is in 50 large measure concealed or rendered inconspicuous. The turned over upper edges of the sheets are then welded together in the manner above described and the template withdrawn through the lower end of the 55 panels. Supplemental closure strips 23 and aprons 24 similar to those associated with the main panel may be employed to finish the assembly and lend an attractive appearance to the bed. It will be understood that the wing panels are frictionally fitted into slots in the supporting legs and soldered thereto.

Both the foot board panel and the wing panels may be embossed in any appropriate manner to enhance their attractive appear-

ance and may be given a finish which will simulate the grain of an ordinary wooden panel.

By my invention I provide a metallic panel of double thickness corresponding 76 closely to the thickness of a wooden bed panel, the top wall of my panel being unitary or integral with the side wall parts, the entity of sufficient strength or stiffness 75 to resist bending. The somewhat unsightly 76 bead commonly employed at the upper edge of the panels and which is an unmistakable indication of the metallic nature of the bed is entirely eliminated. The lines of welding 80 at the top of the panels may be finished and polished in various well known ways so that they are quite inconspicuous. The double panels in themselves have a very desirable heat insulating effect which is particularly useful in case the bed is arranged 85 so that one of its ends is close to a window or radiator. This heat insulating effect may be supplemented if desired by filling the hollow panels with an asbestos or similar light insulating material. 90

It is quite obvious that the shapes, sizes, and curvatures of the panels are entirely optional with the manufacturer and that any shapes and forms demanded by the trade might be made in accordance with my improved process. 95

It will thus be seen that there is herein described apparatus in which the several features of this invention are embodied, and which apparatus in its action attains the 100 various objects of the invention and is well suited to meet the requirements of practical use.

As many changes could be made in the above construction and many apparently 105 widely different embodiments of this invention could be made without departing from the scope thereof, it is intended that all matter contained in the above description or shown in the accompanying drawings shall be interpreted as illustrative and not in a limiting sense. 110

Having thus described my invention what I claim as new and desire to secure by Letters Patent is:

1. An end piece for metal beds including hollow legs, a hollow panel connecting the legs, said panel including a pair of spaced sheets of metal having their upper edges turned over and joined together to provide 120 an uninterrupted surface of the same width as the thickness of the panel, the union of the sheets at the upper edge of the panel being an edge to edge union. 115

2. An end piece for metal beds including hollow legs, a hollow panel connecting the legs, said panel including a pair of spaced sheets of metal having their upper edges turned over and joined together, the union 125 of the sheets at the upper edge of the panel 130

being an edge to edge union, running substantially along the median line of such upper edge.

3. A metal bed including an end piece comprising legs, a hollow panel having its side edges secured within the legs, a closure strip closing the open lower end of the hollow panel and secured in the legs, and a hollow apron below the closure strip and adjacent thereto having its ends secured with respect to the legs.

4. A device of the character described in claim 3 and wherein the legs are suitably slotted to receive the ends of the panel, and of the closure strip, and wherein the apron forms a strengthening brace.

5. A metal bed including an end piece, said end piece including a pair of legs, a hollow panel secured between the legs, curved hollow wing panels having their inner edges secured to the legs, supplemental legs for supporting the outer edges of the wing panels, and closure strips closing the open lower ends of all three panels forming an ornamental protruding bead thereon extending into corresponding anchoring openings in the legs.

6. A metal bed including an end piece, said end piece including a pair of legs, a hollow main panel secured between the legs, said panel comprising a pair of sheet metal side wall parts uniformly spaced throughout their areas, means integral with said side wall parts uniting the latter at the tops thereof, curved hollow wing panels having their inner lateral edges secured to the legs,

supplemental legs for supporting the outer lateral edges of the wing panels, each of said wing panels comprising a pair of longitudinally curved sheet metal side wall parts, uniformly spaced throughout their areas, and means integral with said curved parts uniting the latter at the tops thereof, whereby the entire area of the main panel and the wing panels will be free from projections.

7. An end piece for metal beds including legs, a hollow panel connected between the legs, said panel including a pair of longitudinally curved spaced sheets of metal having sloping upper edges, turned over and joined together to provide an uninterrupted surface of compound curvature and of the same width as the thickness of the panel, the union of the sheets at the upper edge of the panel being an edge to edge union, the ends of said panel extending into the corresponding legs.

8. An end piece comprising four legs, a straight hollow panel secured between the two central legs and hollow curved wing panels secured between the central legs and outer legs, each of said panels including spaced metallic sheets, the upper edges of said sheets being turned over and joined together in substantially abutting relationship to provide uninterrupted panel surfaces of the same thickness as the width of the panel.

Signed at New York in the county of New York and State of New York, this 20th day of August A. D. 1924.

ADOLPH WEISMAN.
